CAR TRUCK

Harold Y. Carpenter, Davenport, Iowa, assignor, by mesne assignments, to McConway & Torley Corporation, Pittsburgh, Pa., a corporation of Pennsylvania

Application September 26, 1941, Serial No. 412,446

3 Claims. (Cl. 105—208.1)

This invention relates to railway car trucks and, more particularly, to trucks of the self-aligning swing motion type for freight cars.

Objects of the present invention are: to provide a truck of the type described which is of simple and rugged construction, which is economical to manufacture, which is easy to assemble, which permits easy removal and replacement of the springs of the side frame without detaching the truck from the car body, and which has a differential cushioning action.

With the above and other objects in view, the invention may be said to comprise the car truck as illustrated in the accompanying drawings, hereinafter described, and particularly set forth in the appended claims, together with such variations and modifications thereof as will be apparent to one skilled in the art to which the invention pertains.

Reference should be had to the accompanying drawings forming a part of this specification, in which:

Figure 1 is a side elevation of a truck embodying the invention, portions of the side frame, transom, and transom spring support being broken away and shown in section;

Fig. 2 is a fragmentary top plan view, with a portion of the transom and spring plank broken away and shown in section; and

Fig. 3 is a section taken on the line 3—3 indicated in Fig. 2.

In the accompanying drawings one side only of the truck is illustrated, it being understood that the opposite ends of the bolster and transom are identical and that the supports for the opposite ends of the transom and bolster are also identical, as is common practice in the art.

Referring to the accompanying drawings, the truck is provided with a side frame 1 which has journal boxes 2 at opposite ends thereof which are connected by top and bottom chords 3 and 4, the top chord 3 being the compression chord and the bottom chord 4 the tension chord. The top and bottom chords 3 and 4 are connected intermediate their ends by guide columns 5 which provide a central opening 6. The columns 5 have upper inwardly offset guide portions 7 provided with opposed concave faces, the guide portions 7 being spaced a substantial distance above the bottom of the opening so that the opening is wider at the bottom.

The truck is provided with a transom which consists of spaced crossbeams 8 and integral end portions 9. The transom is preferably in the form of a one-piece casting, the crossbeams and

end members being of substantially the same depth, hollow and of substantially rectangular cross section.

The end portions of the transom are provided with inclined shoulders 10 which are adapted to engage the inner edges of the guide portions 7 of the columns, and with inclined flanges 11 which overlie the outer edges of the guide portions. The bottom portion of the opening 6 is wide enough to receive the flanges 11, which may terminate short of the top edge of the transom, the height of the flanges 11 being less than the distance between the lower ends of the guide portions 7 and the bottom chord 4, so that the end of the transom may be inserted into the bottom portion of the opening 6 and then lifted into the space between the guide portions 7 of the columns. The shoulders 10 and flanges 11 form flaring channels to receive the guide portions 7, and between the shoulders 10 and flanges 11 the transom is provided with convex portions which are received in the concave faces of the guide portions 7 of the columns.

The portion of the bottom chord 4 extending across the bottom of the opening 6 is of tubular cross section and is provided with a flat, horizontal top wall 13 which has spaced openings 14. A member 15, which serves as a spring support and as a stop for limiting the movement of the transom, is detachably mounted upon the top wall 13 of the bottom chord and has a flat bottom wall 16, which extends substantially the full width of the opening 6 and which is provided with integral positioning lugs 17, which extend into the openings 14 in the top wall 13 of the tubular bottom chord.

The central portion of the member 15 is tubular in form and provides a stop pedestal which has a flat top wall 18, which is connected to the bottom 16 by the integral side walls of the member 15 and by a transverse web 19 which is integral with the top wall 18, bottom wall 16 and sides of the member 15. Transom supporting springs 20 are mounted upon the ends of the bottom wall 16 of the member 15 which project beyond the central stop portion. The springs 20 are preferably of a capacity sufficient to support the transom slightly above the top wall 18 of the spring box when the springs are subjected to the weight of a fully loaded car. The top wall 18 of the spring box limits the downward movement of the transom and prevents exertion of more than a predetermined pressure upon the springs 20.

A suitable cushioning pad 21, which may be

formed of rubber and fabric, may be attached to the upper face of the top wall 18 of the member 15. A spring plank 22 is suspended at each end from the transom crossbeams 8 by means of links 23 connected at their upper ends by pivots 24 to the crossbeams 8, and at their lower ends by pivots 25 to the spring plank adjacent its end.

The spring plank carries cushioning springs 26 at the ends thereof and these springs support the ends of a bolster 27. The weight of the car body is imposed upon the bolster and, through the springs 26 and suspension links 23, upon the transom, which is supported by the springs 20. The springs 20 preferably have a greater deflection rate than the springs 26, so that light loads are cushioned principally by the springs 20. The load transmitted through both sets of springs to the side frames has a softer cushion than would be provided by either set of springs alone. Excessive pressures, however, are imposed solely upon the stiffer cushioning springs 26, which are of sufficient capacity to effectively cushion the heaviest loads.

The differential cushioning action, due to the stopping off of the transom springs, provides a relatively soft cushion for light loads and a relatively stiff cushion for heavy loads. The stop 18 also prevents excessive oscillation of the springs, and serves to break up oscillations of the springs at critical speeds.

It is to be understood that variations and modifications of the specific devices herein shown and described for purposes of illustration may be made without departing from the spirit of the invention.

What I claim is:

1. A car truck comprising side frames, each having a top and bottom chord and spaced guide columns connecting said chords, and providing a centrally disposed opening in the side frame, a combined spring support and stop member detachably mounted on the bottom chord within each opening, said member being of tubular form and having a base portion resting upon said bottom chord and a shorter top wall which serves as a stop, springs mounted upon the base portion

of each of said members, said springs having their upper ends projecting above the top walls of said members, and a transom having its ends positioned in said openings and supported upon 5 said springs above said stop portions.

2. A car truck comprising side frames, each having a top and bottom chord and spaced guide columns connecting said chords, and providing a centrally disposed opening in the side frame, 10 the portions of the bottom chords extending across the bottom of said openings being of tubular form and having a top wall provided with spaced openings, a combined spring support and stop member supported on the bottom chord in each side frame opening, each of said members having a base portion resting upon the top wall of the bottom chord, said base portion extending across the bottom of the opening and having lugs disposed in the openings of said top wall 15 and a stop portion projecting upwardly from said base portion intermediate the ends thereof, springs mounted upon the ends of the base portions of said members and projecting above the stop portions, and a transom having its ends in said side frame openings and supported upon said springs above said stop portions.

3. A car truck comprising side frames, each having a top and bottom chord and spaced guide columns connecting said chords and providing a centrally disposed opening in the side frame, the portion of the bottom chord extending across the bottom of said opening being of tubular form and having a flat horizontal top wall provided with spaced openings, a tubular member of rectangular cross section in the opening of each side frame, each of said members having a flat base resting upon the top wall of a bottom chord provided with lugs projecting into the openings of said top wall, each of said members having a centrally disposed flat top wall of less length than said base and a transverse integral stiffening web centrally of said top wall, springs mounted upon the projecting end portions of said base and projecting above the top wall, and a transom 30 having its ends resting upon said springs.

HAROLD Y. CARPENTER.
